APPARATUS FOR PRINTING UPON
CYLINDRICAL OBJECTS

James J. McElwain, Wheeling, W. Va., assignor
to Wheeling Stamping Company, Wheeling,
W. Va., a corporation of West Virginia

Application October 8, 1940, Serial No. 360,285

11 Claims. (Cl. 101—38)

This invention pertains to the art of printing and is for a machine and method for printing upon the surface of cylindrical bodies such for example as cylindrical bodies or containers formed from molded plastic material and such as impact-extruded containers as for example, collapsible tubes.

At the present time machines for decorating or printing upon the surface of hollow cylindrical bodies are provided in which there is a rotatable support or turret which carries a plurality of mandrels projecting in an axial direction from the turret. These mandrels, while being freely rotatable on the turret, are fixed with reference to the center of the turret. Cooperating with the turret is a printing drum carrying a rubber printing blanket. The blanket is carried by rotation of the printing drum past an inking roll, and then travels around to engage the surface of an article carried on one of the mandrels, and as the printing blanket rolls over the article, the article is rotated and ink is transferred to it from the printing blanket. The turret is advanced in steps so as to progressively present the several mandrels with the articles thereon to the printing drum. After each article has been printed upon it is pulled off the end of the mandrel and another article is applied in its place. While these machines are generally satisfactory for printing upon very thin-walled tubes, such for example as collapsible tubes, considerable difficulty has been found in adapting them to the printing of molded plastic containers having relatively thicker walls for the reason that the bore of the container is not always concentric with the outer cylindrical surface, or because the wall of the article is not uniform, or because the exterior surface of the container is to a very slight extent not a true cylinder. Where any of these conditions exist, the article does not make uniform contact with the printing blanket. Also, the machines have to be set up to operate upon one particular diameter of article with a predetermined wall thickness. If an article of a different diameter is to be decorated or printed upon, or if it has a different wall thickness, different mandrels have to be substituted and the machine otherwise changed.

According to the present invention, there is provided an improvement in machines of this general character wherein the mandrels instead of being fixed with respect to the center of the turret on which they are mounted, are mounted in such manner that they may have a limited movement toward or away from the center of

the turret, and means is provided for resiliently urging the mandrels away from the center.

This arrangement of the mandrels enables the machine to automatically compensate for such variations as occur in molded plastic tubes or other objects to be decorated. It also enables adapters to be used whereby within certain ranges, the same mandrels may be employed for the printing of articles of different diameters or different wall thicknesses without requiring any change in the set-up of the machine which would require a minimum change.

The invention further contemplates constructing the mandrels in such manner as to allow the articles to be printed upon to have some slight universal movement with respect to the axis of the mandrel so that the article will adjust itself to the surface of the printing blanket and thus assure more uniform printing.

20 The invention includes the step in the method of printing of supporting the article in such a way that it will automatically adjust itself in contact with the printing surface and also the step which includes the use of an adapter.

25 The invention may be readily understood by reference to the accompanying drawings which illustrate one embodiment of my invention and in which

Figure I is a more or less schematic side view of a printing machine equipped with my invention;

30 Figure II is a side elevation on a larger scale of a portion of the turret which carries the mandrels showing the mounting for one of the mandrels;

35 Figure III is a top plan view of that portion of the machine which is shown in Figure II;

40 Figure IV is a side elevation of a molded vial which the present invention is particularly adapted to print upon;

45 Figure V is a side elevation of a portion of the machine shown in Figure I, but on a larger scale showing the parts in the position that they occupy at the moment when the printing blanket is engaging an article on one of the mandrels;

Figure VI is a transverse fragmentary section in the plane of line VI—VI of Figure V with the surface of the printing blanket shown in elevation;

50 Figure VII is a view generally similar to Figure VI showing the application of my invention to the printing of thin-walled collapsible tubes by the use of an adapter;

55 Figure VIII is a side elevation of one of the adapters;

Figure IX is a transverse section in the plane of line IX-IX of Figure VIII; and

Figure X is a detailed view showing partly in elevation and partly in section an adapter of different over-all diameter removed from the mandrel.

Referring to the drawings, the printing machine is of a type now generally well known in the art. It is provided with a supporting frame 2 which carries a drum 3 upon a portion of the surface of which is mounted a printing blanket 4. The blanket 4 is usually made of a resilient rubber. A series of rolls transfers ink from a pot 6 to the type carried by a printing roller 5, and roller 5 transfers the ink in the pattern of the type on the surface of the printing blanket 4. The rotation of the printing roller and inking rolls is accomplished by the drum 3 which moves the blanket 4 over the surface of the roller 5. Cooperating with the printing drum is an indexing drum or turret 7 having a mechanism 8 of a type well known to those skilled in the art for rotating the turret 7 in a step-by-step fashion. Machines as so constructed are now generally known to the art. Heretofore the turret 7 has been provided with a plurality of mandrels projecting from the end face thereof, these mandrels being fixed but freely rotatable with respect to the axis of the drum. The indexing mechanism for rotating the turret is arranged so that each mandrel in succession is normally held on a line of centers between the two drums in such position that an article on the surface of the mandrel will be engaged by the blanket 4 as the drum 3 is rotated. The present invention pertains primarily to the construction and arrangement of the mandrels.

According to the present invention the drum or disk 7 is provided at regularly spaced intervals with transverse pins 10 which pass therethrough. Secured to one end of each pin 10 is an arm 11 and secured to the other end of each pin is a generally similar arm 12 which is on the opposite face of the disk 7 from the arm 11. The arms 11 and 12 are provided with aligned bearings 13 for supporting a spindle 14, the bearings enabling the spindle to rotate freely. The spindle 14 passes through an elongated opening 15 in the disk 7. Each of the arms 11 and 12 is provided with a set screw 16 having a disk 17 thereon that engages a compression spring 18. The opposite end of the spring 18 is supported against an abutment 19 provided on the face of the rotatable head or disk 7. The arm 11 is fast to the pin 10, and the arm 12 is also fast to the end of the pin 10 so that the assembly comprising the pin 10 and the arms 11 and 12 is a unit carrier for supporting the spindle 14. The spring 18 tends to yieldably urge the spindle outwardly away from the center of the disk 7, and the slot 15 through which this spindle passes limits the range of movement of the spindle toward and away from the center.

Projecting from one end of the spindle 14 is a mandrel 14a. This mandrel is preferably made larger at the center than at its ends, preferably being slightly convexed.

In the operation of the machine for the decoration of molded cylindrical objects such for example as the vials A shown in Figures IV and VI, which for example may be of plastic material or glass, the vials are slipped onto the mandrels in a position remote from the printing position. As the disk 7 rotates, the vials are advanced progressively to the printing position. The

7 springs 18 normally serve to hold the mandrels in a position where they are most remote from the center of the disk or drum 7. When the vials on the mandrels are engaged by the printing blanket, the pressure may cause the mandrel to be moved toward the center of the drum 7. Because of the fact that the article on the mandrel is yieldably pressed by the spring 18 against the printing surface, the printing is uniform notwithstanding that there may be certain irregularities in the vial due to the inside not being concentric with the outside or due to inequalities of the wall thickness or due to the article not being truly cylindrical. Moreover, because of the contour of the mandrels, the cylindrical articles adjust themselves on the mandrels so as to press uniformly against the printing blankets. The resilient mounting of the mandrel in combination with the universal movement which the article has on the mandrel by reason of the convex contour of the mandrel thus enables the article to be evenly and uniformly decorated or printed upon.

27 The same machine may be used for printing upon easily deformable thin-walled receptacles such for example as collapsible tubes. Where the machine is to be used for printing upon collapsible tubes, the end of the mandrel 14a is preferably provided with a projecting stud 20 which is necked-in. Slipped over the mandrel 28 is an adapter 21 in the form of a sleeve having rigid walls. The outer end of the sleeve is closed by a plug 29a, and on the inner end of this plug is a clip 22. This clip snaps over the necked stud 20 and thus holds the adapter against longitudinal movement on the mandrel. At the same time the clip is sufficiently resilient and engages the stud loosely enough so that the adapter can adjust itself on the convexed mandrel. The adapter is necessary in order to support the tube and prevent it from being deformed during the operation of printing. The adapter of course is generally similar in its contour to the vial A described in connection with Figures I to VI inclusive. The tube, designated B in Figure VII, closely fits over the adapter so that for all practical purposes the tube and the adapter together become a single unit on the mandrel.

40 Where a tube of larger diameter is to be printed upon, the adapter 21 as shown in Figure X, has a thicker wall but has the same internal diameter. The wall thickness is such that the adapter will fit snugly into the tube. Because of the fact that the mandrel which carries the 45 adapter may move under pressure toward the center of the drum or turret on which it is carried, the adapter of larger diameter may be used without changing the printing machine except insofar as a larger diameter tube may require some 50 change in the printing blanket.

The resilient support of the mandrels also enables thicker and more elastic printing or transfer blankets to be used on the printing drum, and this is desirable because it permits of greater 55 tolerances in the machine without sacrifice of results.

While I have illustrated and described in detail one preferred embodiment of my invention, it will be understood that this is merely by way 60 of illustration and that various changes and modifications may be made in the construction of the machine within the contemplation of my invention and within the scope of the following 65 claims.

I claim as my invention:

1. Printing apparatus of the class described comprising a rotatable head, a carrier on the head movable toward and away from the center thereof, a rotatable mandrel on the carrier, and means for yieldably urging the carrier in a direction away from the center of the head, said mandrel having a container-supporting surface thereon of larger diameter at the center than at its ends.

2. Printing apparatus of the class described comprising a rotatable head, a pair of arms, one at each side of the head, a pin fastened through the head on which the arms are mounted, a spindle rotatably mounted in the two arms and projecting in an axial direction from the end of the head, the head being slotted in a generally radial direction to enable the arms with the mandrel supported thereby to move arcuately to a limited extent toward and away from the center of the head, means for resiliently pressing the arms outwardly toward the periphery of the head, and a printing drum cooperating with the mandrel.

3. Printing apparatus of the class described comprising a turret having a plurality of mandrels projecting in an axial direction therefrom and having a printing drum cooperating with the mandrels characterized by the provision of means for yieldably supporting the mandrels for movement in a direction toward and away from the center of the turret, and an adapter slidably carried on the mandrel for ready removal said adapter having a substantially cylindrical bore and said mandrel having an adapter holding portion which is convex, and resilient interengaging means between said mandrel and said adapter.

4. Printing apparatus of the class described comprising a turret having a plurality of mandrels projecting in an axial direction therefrom and having a printing drum cooperating with the mandrels, means for yieldably supporting the mandrels for movement in a direction toward and away from the center of the turret, and an adapter removably carried on the mandrel said adapter having a substantially cylindrical bore and said mandrel having an adapter holding portion which is convex, and resilient interengaging means between said mandrel and said adapter, whereby, the adapter is supported on the mandrel in such manner that it may wobble to a limited extent.

5. For use in a printing machine of the class described wherein there is a rotatable head having a plurality of axially projecting mandrels arranged about the center, a carrier mounted on the head movable toward and away from the center, a mandrel rotatably supported in said carrier, and means for resiliently urging the carrier outwardly away from the center of the drum, said mandrel having a work-holding portion which is convexed.

6. For use in a printing machine of the class described wherein there is a rotatable head having a plurality of axially projecting mandrels arranged about the center, a carrier mounted on the head movable toward and away from the center, a mandrel rotatably supported in said carrier, means for resiliently urging the carrier outwardly away from the center of the drum, said mandrel having a work-holding portion which is convexed, a rigid adapter on the work-holding portion of the mandrel having a cylindrical internal bore substantially equal to the maximum diameter of the work-holding portion of the

mandrel, and means for releasably holding the adapter on the end of the mandrel.

7. For use in a printing machine of the class described wherein there is a rotatable head having a plurality of axially projecting mandrels arranged about the center, a carrier mounted on the head movable toward and away from the center, a mandrel rotatably supported in said carrier, means for resiliently urging the carrier outwardly away from the center of the drum, said mandrel having a work-holding portion which is convexed, a rigid adapter on the work-holding portion of the mandrel having a cylindrical internal bore substantially equal to the maximum diameter of the work-holding portion of the mandrel, and means for releasably holding the adapter on the end of the mandrel, said means comprising a resilient clip on the inner end of said adapter, the mandrel having a neck-like stud at the end thereof for cooperation with the clip.

8. A unit for attachment to turret type printing machines for adapting such machines to the printing of cylindrical objects, such as soft collapsible tubes, comprising a mandrel having a convexed working portion, a carrier providing a bearing for one end of the mandrel, means for pivotally supporting the carrier on a turret, means for yieldably urging the carrier outwardly away from the axis of the carrier, a rigid cylindrical adapter fitted over the working portion of the mandrel having a cylindrical interior substantially equal in diameter to the maximum diameter of the convexed portion of the mandrel and having a cylindrical exterior of a diameter to have a sliding fit in the article to be printed upon, and means for releasably holding the adapter against endwise movement on the mandrel but permitting the same to wobble on the convexed portion of the mandrel.

9. Printing apparatus of the class described comprising a rotatable head, a pivoted carrier on the head movable in an arc toward and away from the center thereof, a rotatable mandrel on the carrier, and means for yieldably urging the carrier in a direction away from the center of the head, the pivot about which the arcuate movement of the carrier takes place being to one side of a radius extending from the center of the head to the center of the mandrel, and means for limiting the movement of the carrier, whereby the center of the mandrel may never be in line with a radius extending from the center of the head to the center about which the carrier pivots, the pivot of said carrier being located in advance of said mandrel with respect to the direction of movement of said head, said pivot being radially nearer the center of said head than said mandrel when said mandrel is moved away from the center of said head.

10. For use in printing apparatus having a printing drum and a rotatable head, a carrier pivotally supported on the head movable in an arc about its pivot point toward and away from the periphery thereof, bearings in the carrier eccentric to the pivot point thereof and a mandrel rotatably supported in the bearings, means for yieldably urging the carrier in a direction away from the center of the head, and means whereby the arcuate movement of the carrier is limited to a range where a radius from the center of the head to the center of the mandrel is always angularly displaced to a radius from the center of the head to the center of the pivot, the pivot of said carrier being located in advance of said

mandrel with respect to the direction of movement of said head, said pivot being radially nearer the center of said head than said mandrel when said mandrel is moved away from the center of said head.

11. Printing apparatus of the class described comprising a printing drum, a rotatable head cooperating with the drum having a plurality of carriers thereon, a mandrel mounted in each carrier, each carrier with its mandrel being pivotally supported to permit a limited movement of the mandrel in an arc toward and away from the center of the drum, resilient means for urging the carrier and the mandrel in a direction

away from the center of the drum, and means for limiting the arc of movement of the carriers and mandrels, to an extent such that the pivot point of each carrier is always circumferentially offset from a radius extending from the center of the head to the center of the mandrel on the carrier, the pivot of said carrier being located in advance of said mandrel with respect to the direction of movement of said head, said pivot being radially nearer the center of said head than said mandrel when said mandrel is moved away from the center of said head.

JAMES L. McELWAIN.
